UNITED STATES PATENT OFFICE.

JAMES A. ADAMS, OF WALTHAM, MASSACHUSETTS, ASSIGNOR TO THE BOSTON MANUFACTURING COMPANY, OF WALTHAM, MASSACHUSETTS, A CORPORATION OF MASSACHUSETTS.

DESIGN FOR A TEXTILE FABRIC.

Application filed April 8, 1924. Serial No. 9,200. Term of patent 3½ years.

To all whom it may concern:

Be it known that I, JAMES A. ADAMS, a citizen of the United States residing at No. 27 Pleasant Street, Waltham, in the county of Middlesex and State of Massachusetts, have invented a new, original, and ornamental Design for Textile Fabrics, of which the following is a specification, reference being had to the accompanying drawing, forming a part thereof.

The figure is a plan view of a portion of a textile fabric showing my new design. The black lines shown in the drawing represent

cord showing upon the face of the fabric held in place by the weft threads. The background consists of warp and weft threads. Contrasting colors may be used to bring out the design.

I claim:

The ornamental design for a textile fabric as shown.

JAMES A. ADAMS.
